D 13,387

EX

No. 13,387

Oct 31, 1882

UNITED STATES PATENT OFFICE.

JOHN L. POPE, OF CLEVELAND, OHIO.

DESIGN FOR A WEAR-IRON.

SPECIFICATION forming part of Design No. 13,387, dated October 31, 1882.

Application filed August 2, 1882. Term of patent 7 years.

To all whom it may concern:

Be it known that I, JOHN L. POPE, of Cleveland, in the county of Cuyahoga and State of Ohio, have invented and produced a new and original Design for Wear-Irons, of which the following is a specification, reference being had to the accompanying engraving, forming part thereof.

My invention relates to a design for wear-irons used particularly on carriages and other vehicles; and its novelty consists in its surface ornamentation and in its general configuration, as will be hereinafter more particularly described and claimed.

In the accompanying engraving the upper or exposed face of the iron is ornamented by a depressed or sunken portion, *a*, running outwardly, as at *d*, and forming the ribs or beads *b* and *c*. Those portions of the iron cast or bent at angles to the shank *e* thereof curve outward gradually and give to the article an im-

proved shape or form. At the extremities of these outwardly running and curved portions are holes, as usual, for securement of the iron by proper means to the desired part of the vehicle.

What I claim as of my invention, and desire to secure by design Letters Patent, is—

1. A wear-iron having the sunken portion *a*, which runs outwardly, as at *d*, and having the ribs or beads *b* *c*, substantially as shown and described.

2. A wear-iron of substantially the shape shown—that is, with a straight shank and with outwardly running and curved portions, as described.

In testimony whereof I have hereunto set my hand this 22d day of June, 1882.

JOHN L. POPE.

In presence of—

CHAS. W. MOSES,
C. M. COPP.
